UNITED STATES PATENT OFFICE

ELIOT FARLEY AND NATHANIEL R. LANDON, OF MOUNT KISCO, NEW YORK, ASSIGNEES TO DELAWARE, LACKAWANNA & WESTERN COAL COMPANY, OF NEW YORK, N. Y., A CORPORATION OF NEW JERSEY.

METHOD OF TREATING COAL AND PRODUCT THEREOF

No Drawing.

Application filed February 25, 1929. Serial No. 342,600.

This invention relates to the treatment of "storage" anthracite coal to remove therefrom the surface discoloration which takes place in storage and to restore essentially the original appearance of the fresh mined coal.

Fresh mined coal, that is coal which is mined and shipped for immediate consumption has a jet black color and a bright luster. Owing to the seasonal demand for coal, large quantities of fresh mined coal are placed in storage whenever possible in order to avert a shortage in the fall and winter months. Such coal is known in the trade as "storage" coal.

Coal so stored does not deteriorate as a fuel but the physical appearance is altered. The coal becomes a dull grey in appearance and a considerable portion of it becomes badly discolored by metallic compounds. The consuming public, who are accustomed to recognize anthracite coal by its jet black color and luster often assume that coal which has been held in storage and has thus lost its characteristic appearance is poor in quality. The original "fresh mined" coal appearance cannot be restored by ordinary washing. Consequently serious losses are sustained by the producer because this storage coal does not command the price of "fresh mined" coal, although analysis indicates that the change is only one of appearance and there is no loss of fuel value or consequential change in chemical composition.

It is the object of the present invention to provide a method of treating storage coal to remove the surface discoloration and restore its original characteristic color and bright luster.

The iron in the mineral matter of coal is considered to be almost wholly present in combination with sulphur. Under the influence of atmospheric exposure the iron sulphides become oxidized presumably to insoluble basic sulphates, oxides, and other compounds imparting to the coal a rusty appearance. Other reactions go on and other metallic compounds may show on the surface. The longer the coal is in storage and consequently the longer it is exposed to atmospheric influences the greater usually becomes the discoloration. So far as we are aware, these dis-

colorations have never been removed in a practical way by any previous known treatment.

We have discovered that the surface discoloration of storage coal can be removed and the original appearance of the coal restored by treating the coal under appropriate conditions with acids or with acid salts. Numerous acids and acid salts, of which oxalic acid, formic acid, hydrochloric acid, acid fluoride of soda and sodium acid fluo-sulfate are examples, can be used and the selection will depend on questions of economy and the nature and degree of the discoloration. We, therefore, do not limit ourselves to any particular acid or acid salt or to single acids, as mixed acids and acid salts can be used. For the treatment of badly discolored coal, among the acids, oxalic acid is particularly efficient, and of the acid salts, sodium acid fluosulphate is effective.

As an example of the method, we may proceed as follows,—ten parts of oxalic acid crystals are dissolved in one hundred parts of water and the discolored coal is immersed in this solution at normal temperatures for a period sufficient to accomplish the object, usually a few minutes, after which the coal is removed from the solution and may be washed or sprayed with water.

The action is more rapid and thorough if the coal is agitated in the solution, thereby producing a scrubbing action. A practical means of accomplishing this action is by use of a "jig", well known in the coal industry as an apparatus of separating coal from impurities, the principle of which is based on the difference in specific gravity of coal and rock or slate. This separation in the preparation of domestic sizes of anthracite is accomplished in a large tank filled with water. The action of a plunger about two feet below the surface floats the coal to the surface, whence it can be removed. Instead of water, the jig is filled with acid solution when it is desired to treat coal for the purpose of removing the discoloration.

While we have described the use of a 10% solution of oxalic acid at normal temperature, by treating the coal at higher tempera-

tures less concentrated acid can be used, for instance a 1% solution is quite efficient even on badly discolored coal at a temperature approaching the boiling point of the solution.

5 A solution of sodium acid fluosulphate can be used in much the same way as the oxalic acid solution. This acid salt not being as readily soluble as oxalic acid, it is better to treat the coal with it at temperatures above normal.

10 The acid solution can be recovered and be reused until it becomes too heavily contaminated with substances dissolved from the coal, the degree of acidity being maintained 15 by the periodic addition of small quantities of acid or acid salt.

15 As indicated herein, this invention is not restricted to the application to the coal of any particular acid solution, the essence of 20 this invention residing particularly in the restoration of the original color and luster of the coal. Various changes may be made, therefore, in the procedure and the chemicals employed herein without departing from the 25 invention or sacrificing any of the advantages thereof.

We claim:

1. Anthracite coal that has become discolored treated with an acid to remove therefrom the discoloration.

20 2. Anthracite coal that has become discolored treated with oxalic acid to remove therefrom the discoloration.

3. The method of restoring the luster and 35 improving the appearance of coal which comprises treating the coal with an acid capable of removing the discoloration therefrom.

4. The method of restoring the luster and 40 improving the appearance of coal which comprises treating the coal with an acidic solution capable of removing the discoloration therefrom.

5. The method of restoring the luster and 45 improving the appearance of discolored coal which comprises treating it with oxalic acid.

In testimony whereof we affix our signatures.

ELIOT FARLEY.
NATHANIEL R. LANDON.

DISCLAIMER

1,748,335.—*Eliot Farley and Nathaniel R. Landon, Mount Kisco, N. Y. METHOD OF TREATING COAL AND PRODUCT THEREOF.* Patent dated February 25, 1930. Disclaimer filed March 3, 1936, by the assignee, *Delaware Lackawanna & Western Coal Company*.

Hereby disclaims:

(a) Claims 1 and 2 of said Letters Patent.

(b) From claims 3 and 4 of said Letters Patent "any and all methods of restoring the luster and improving the appearance of coal by treating the coal with an acid or acidic solution in which the acid or acidic solution does not consist of oxalic acid, formic acid, hydrochloric acid, acid fluoride of soda, or sodium acid fluosulphate or mixtures thereof."
